UNITED STATES PATENT OFFICE.

HERMANN SIEGEL, OF NEW YORK, N. Y., ASSIGNOR TO L. STRAUS & SONS,
OF NEW YORK, N. Y.

DESIGN FOR A GLASS VESSEL.

SPECIFICATION forming part of Design No. 37,353, dated February 28, 1905.

Application filed January 27, 1905. Serial No. 242,981. Term of patent 7 years.

To all whom it may concern:

Be it known that I, HERMANN SIEGEL, a citizen of the United States, residing in the city of New York, borough of Manhattan, and State of New York, have invented a new, original, and ornamental Design for Glass Vessels, the same being disclosed as applied to a bowl in the accompanying drawings, in which—

Figures 1 and 2 are elevations, and Fig. 3 is to a bottom plan.

What I claim as new, and desire to secure by Letters Patent, is—

The ornamental design, as herein shown, for a glass vessel.

HERMANN SIEGEL.
